UNITED STATES PATENT OFFICE

151,520

DESIGN FOR A PERFUME BOTTLE

Jerusha K. Liello, New York, N. Y.

Application September 27, 1946, Serial No. 133,606

Term of patent 7 years

(Cl. D58—6)

To all whom it may concern:

Be it known that I, Jerusha K. Liello, a citizen of the United States, residing in New York city, county of New York, and State of New York, have invented a new, original, and ornamental Design for a Perfume Bottle, of which the following is a specification, reference being had to the accompanying drawing, forming part thereof.

In the drawing:

I claim:

The ornamental design for a perfume bottle, as shown.

JERUSHA K. LIELLO.
